UNITED STATES PATENT OFFICE.

LEVI G. JOHNSON, OF APPLE, MINNESOTA.

TONGUE-TRUCK FOR HARVESTERS.

No. 882,113.

Specification of Letters Patent. Patented March 17, 1908.

Application filed May 14, 1907. Serial No. 373,552.

To all whom it may concern:

Be it known that I, LEVI G. JOHNSON, a citizen of the United States, residing at Apple, in the county of Marshall and State of Minnesota, have invented a new and useful Tongue-Truck for Harvesters, of which the following is a specification.

This invention has relation to tongue trucks for harvesters and it consists in the novel construction and arrangement of its parts as hereinafter shown and described.

The object of the invention is to provide a tongue truck having its parts so arranged that the tongue may buckle laterally at the end of a swath in order that the harvester may be readily turned at a true right angle and the sickle bar thereof may enter initially into the new swath along its entire length, thereby, preserving rectangular relation of the adjacent swaths and avoiding bowing at the initial ends of the swaths.

In the accompanying drawings:—Figure 1 is a top plan view of the tongue truck. Fig. 2 is a transverse sectional view of the same cut on the line 2—2. Figs. 3, 4 and 5 are top plan views of the truck in different positions. Fig. 6 is a top plan view of the truck showing a slightly different arrangement of the parts thereof. Fig. 7 is a perspective view of a rod used upon the truck. Fig. 8 is a side elevation of the truck. Fig. 9 is a diagrammatic view of a harvester fitted with the tongue truck and showing the courses taken by the different parts when turning a corner in the grain field. Figs. 10 and 11 are plan views of the draft bar with parts broken away showing different arrangements of the draft chain. Fig. 12 is a transverse sectional view of the tongue showing the manner of attaching an arm to a shaft used in the truck.

The tongue truck is used in combination with the stub tongue 1 and the tongue proper 2. The stub tongue 1 is attached to the frame of a harvester in the usual manner and is held at the proper angle with relation thereto by means of the tilting bar 3 which passes vertically through the stub tongue 1 and is provided at a point above the stub tongue 1 with a cotter pin 4 which may be passed through any one of the perforations 5 and a coil spring 6 interposed between the cotter pin 4 and the upper surface of the stub tongue 1. The upper end of the tilting rod 3 is attached to the harvester as indicated by dotted lines in Fig. 8. The spring 6 is under

tension with a tendency to hold the tongue 1 away from the cotter pin 4. The cotter pin 7 passes through the lower portion of the rod 3 and is adapted to limit the downward movement of the tongue 1 along the said rod. By this arrangement of the tilting rod and stub tongue it will be seen that the frame of the harvester may rock to a limited degree in the line of draft without raising or lowering the forward end of the stub tongue. As the said frame rocks forwardly the spring 6 will be compressed and serve as a check while as the said frame rocks rearwardly the weight of the forward end of the stub tongue and its attachments will serve as a check. The crank shaft 8 passes vertically through the tongue 1 and the ground wheel 9 is journaled upon the crank end of the said shaft 8. The said wheel 9 is provided upon its periphery with an annular flange 10 which is located midway of the side faces of the said wheel.

The shaft 8 is journaled for rotation in the tongue 1 and the wheel 9 normally travels upon the grain side of the tongue 1; when turning the harvester, however, the said wheel may swing under the said tongue. The arm 11 is adjustably attached to the upper end of the shaft 8 and is provided with a series of perforations 12. The tongue clevis 13 is pivoted to the end of the stub tongue 1 but is limited to relative lateral movement only. The tongue proper 2 is pivoted in the clevis 13 but is limited to swing vertically only. The bar 14 is pivoted to the end of the stub tongue 1 and is provided with a series of perforations 15. The bars 11 and 14 extend grainward from the stub tongue 1. The clevis 13 is provided at its side with the eyes 16 and the rod hook 17 enters one of the said eyes at its hooked end and is threaded at its opposite end and enters the collar 18. Said collar 18 is provided with a shank 19 which is adapted to enter any one of the perforations 15 and is held therein by a cotter pin 20. A similar rod 21 connects the bars 11 and 14 together in a similar manner. The draft rods 22 cross the stub tongue 1 diagonally and are attached at their forward ends to the draft bar 23. Said draft bar is attached to the forward portion of the stub tongue 1 and extends stubbleward therefrom. The rear end of the draft rod 22 is adapted to be connected with the frame of the harvester. The draft bar 23 is provided with the pulleys 24 located at proper intervals along the same and upon a draft chain

25 may be so mounted as to require the use of two, three or four draft animals. As this mechanism refers more particularly to draft equalizers than tongue trucks its arrangement will not be described in detail. The doubletrees 26 are connected with the ends of the draft chain 25 and the swingletrees 27 are mounted upon the said doubletrees. The fender rod 28 is erected at the forward portion of the stub tongue 1 and is adapted to prevent the lines or reins from becoming tangled with the harvester reel when a turn is made.

15 From the foregoing description it is obvious that the bar 11 may be extended from the shaft 8 in a parallel line with the crank end of the said shaft and the parts may be so adjusted that the bar 14 will lie parallel with the bar 11. Such an adjustment is desired when a certain number of draft animals are used as it equalizes the lateral strain upon the animals when making a turn. When, however, another number of draft animals are used the bar 11 may be shifted out of its 25 parallel linear relation with the crank end of the shaft 8 and the bar 14 may be inclined with relation to the said bar 11. It is obvious that a multiplicity of adjustments may be accomplished in order to meet various 30 conditions presented under existing circumstances.

Having described my invention what I

claim as new and desire to secure by Letters-Patent is:-

1. In combination with a tongue proper and a stub tongue, means pivotally connecting said tongues together for relative lateral movement only, a crank shaft journaled in the stub tongue, a ground wheel journaled upon the crank of the said shaft, a bar attached to said shaft, a second bar pivoted to the stub tongue, a means connecting said bars together and a means connecting the last said bar with the means pivotally connecting the tongues together. 40

2. In combination with a tongue proper and a stub tongue, a clevis pivoted to the stub tongue for lateral movement only and pivotally connected with the tongue proper, whereby the latter may swing vertically, a 45 crank shaft journaled in the stub tongue, a ground wheel journaled upon the crank of said shaft, an arm adjustably fixed to said shaft, a bar pivoted to the stub tongue, an adjustable rod connecting said arm and bar 50 together, and an adjustable rod connecting said bar with the clevis.

In testimony that I claim the foregoing as my own, I have hereto affixed my signature in the presence of two witnesses.

LEVI G. JOHNSON.
